UNITED STATES PATENT OFFICE

WILLIAM V. ORR, OF CLEVELAND HEIGHTS, OHIO; THE CLEVELAND TRUST COMPANY
AND ADELE MARY ORR EXECUTORS OF SAID WILLIAM V. ORR, DECEASED

CENTRIFUGAL DRIER

Application filed May 6, 1929. Serial No. 360,664.

The invention relates to a machine or apparatus for drying clothes by centrifugal action in a rapidly rotating receptacle, and one object of the improvement is to balance the weight of the receptacle and its contents, so that it will rotate without wobbling or undesirable vibrations.

In machines or apparatus of this type, the rotating receptacle is frequently mounted on the upper end of a vertical shaft or spindle and in order to attain the best results it is desirable, if not necessary, to rotate the receptacle at some 1200 R. P. M.

In practice, however, it has been found that when placing wet clothes in the receptacle, there is usually such a difference in the weight thereof at different points more or less remote from the axis as to cause the receptacle to vibrate on its axis to such an extent as will seriously impair if not destroy the machine, especially when it is rotated at a speed of 900 R. P. M. and upwards.

This difficulty is avoided by the present improvement, in which the clothes receptacle is mounted within a surrounding vessel shaped to form a spherical-zone annular groove or channel of substantial width and depth into which water extracted from the clothes is thrown by centrifugal force to form a liquid fly wheel around the outside of the receptacle and fully spaced therefrom of sufficient weight to dominate and render ineffectual and inconsequential the ordinary differential weight of the clothes in one side or the other of the receptacle.

Another object of the improvement is to provide means which may be selectively actuated by closing the lid of the apparatus for starting a rotation of the spindle on which the clothes receptacle is mounted, and by which the rotation will be automatically stopped by an opening of the lid; but which cannot possibly be actuated without first opening and then closing the lid.

This object is attained in the present improvement by mounting the vertical spindle for limited endwise movement, with vertically movable friction driving means and friction brake means for starting and stopping rotation of the spindle; and by provid-

ing a stationary case around the rotating parts, with a lid hinged at one side thereof having a normally inactive cam on the hinge pintle arranged to be selectively rendered active by manual means during the closing 55 of the lid, to depress a plunger and operate a lever for raising the driving means and releasing the brake means by a closing of the lid, and automatically permitting a release 60 of the driving means and an engagement of the brake means by a subsequent opening of the lid.

The improvement is illustrated in the accompanying drawings forming part hereof, 65 in which

Figure 1 is a vertical axial section of the apparatus, showing all the parts in operating position;

Fig. 2, a section as on line α — α , Fig. 1, when the lid is opened;

Fig. 3, a section as on line α — α , Fig. 1, when the lid is closed; and

Fig. 4, a perspective view of the cam sleeve.

Similar numerals refer to similar parts throughout the drawings.

The apparatus includes a spherical vessel 5, made of cast, stamped or spun metal or the like, which is secured as by a head 5' to the upper end of an upright spindle 6 mounted for limited endwise movement in a lower bearing 7 and an upper bearing 8 on a frame 9 adapted to be secured, as by bolting to the side of a washing machine or other support.

The clothes receptacle 10 is made of sheet metal or the like, and is mounted in the spherical vessel 5 with its bottom 10a seated on the bottom 5a of the vessel and having an annular bracket 11 secured around its upper end portion seated upon the rim 5b of the spherical vessel.

The lower end portion 10b of the receptacle 10 is tapered outward from the bottom upward as an inverted truncated cone, immediately above which is provided an annular series of apertures 10c for discharging water from the receptacle to the vessel; which series of apertures is located immediately below the annular bracket 11 which is preferably provided with a downturned flange 11a for 100

deflecting the water downward into the receptacle.

In the operation of the apparatus, a batch of wet clothes is placed in the receptacle, and if there is not sufficient water in the clothes for the purpose of the present invention, additional water may be poured into the receptacle; after which the spindle is rotated in the manner presently to be described, and the rotation of the vessel secured thereon, rotates the receptacle by its bottom and bracket bearing contacts therewith, until a speed of some 1200 R. P. M. is attained.

In this operation, the water is centrifugally extracted and is thrown outward against the inverted conical zone wall 10b in the side of the receptacle and the inclination of the wall carries the water upward, whence it is discharged through the annular series of apertures 10c into the surrounding spherical vessel, whereupon the water is thrown centrifugally outward into the channel formed by the spherical zone in the periphery of the vessel which channel has a substantial width and depth, to form a continuous water balance wheel of substantial volume as at 13; whence an excess of water may find its way outward through an annular series of liquid outlet apertures 5c immediately below the spherical-zone channel and located freely outward a greater distance from the axis of the receptacle and the vessel than the radius of the receptacle; or when the speed is reduced, the water will find its way downward and outward through the annular series of apertures 5d around the bottom portion of the vessel.

It will be seen that this water balance wheel will have a substantially uniform segmental cross section throughout its peripheral length spaced freely from the outside of the receptacle.

A stationary case 14, preferably made of sheet metal, is provided around the vessel, and may be secured to an annular supporting bracket 9a formed or mounted on top of the bracket 9 around the upper end of the spindle 6, in which bracket is formed an annular trough 9b provided with an outlet 9c for receiving and delivering the water discharged into the case from the rapidly rotating vessel.

During the rapid rotation of the vessel and the receptacle therein the water wheel maintained in the spherical zone periphery of the vessel exerts such a dominating, balancing, stabilizing or gyrating influence as to overcome and render inconsequential the relatively slight differential weight of the clothes in different parts of the receptacle, and thereby prevents a wobbling or vibration of the parts superposed on the spindle.

The stationary case 14 is provided with a lid 15 hinged by ears 15a secured as by a pin 15b on a pintle 16 journaled in bearings 17

and 17' secured as by a bracket 18 to the side of the case.

The bearing 17 is extended outward and recessed to form an annular socket 17a for receiving telescopically one end of a sleeve 19 feathered for endwise movement on the pintle, the inward movement of which sleeve is resisted by a coiled compression spring 20 in the socket around the pintle.

The outer end of the sleeve 19 is provided with a disk handle or button 19a and is also recessed to form the socket 19b for receiving a nut 16a screwed on an axial bolt 16b extending from the end of the pintle, and a washer 21 is clamped by the nut against the end of the pintle for bearing on the bottom 19c of the socket 19b, and stopping the outward movement of the sleeve 19.

A cam 19d is provided on the outer end of the sleeve 19 immediately inside of the disk handle or button, and a flange 19e is provided on the inner side of the cam for the purpose presently to be described.

A plunger rod 22 is mounted for endwise movement in bearings 23 and 23a formed or secured respectively on the bracket 18 and the bearing 8, upon the upper end of which rod is mounted a roller wheel 24 for riding alternately the cylindric sleeve and upon the cam protruding therefrom, when the same is in its outward and inward positions.

The lower end of the plunger rod is supported on the outer end of a lever 25 pivoted at 26 to the lower end of the bearing 7, the lower end of the rod being seated in a cup 25a and adjustably supported by a take-up screw 27 on the end of the lever.

The inner end of the lever 25 is extended upward to form a finger 25b for centrally supporting a sleeve cup 28 in the lower end of the bearing 7; and a ball 29 is located in the cup, upon which rests the lower end of a sleeve shank 30 slidably journaled in the bearing 7, on the upper end of which sleeve is formed or secured the drive wheel 30a having a depending flange 30a' on its rim provided with a V-socket 30a'' by which the wheel may be continuously rotated by a belt 31 from any suitable source of power.

Upon the upper side of the wheel 30a is located a disk 32 made of friction material, upon which may bear flatwise a friction disk 33 secured to the lower end of the spindle 6 as by the flange sleeve 34 and the pin 34a on the lower end portion of the spindle; and a thin steel washer disk 35 may be interposed between the friction disks to ease the starting of the spindle.

A reduced end 6a of the spindle extends downward and is slidably journaled in the sleeve shank 30 of the driving wheel, and by raising the driving wheel as by a depression of the plunger rod 22, the friction disk 32 and the washer disk 35 will be elevated to bear upward against and engage the friction

disk 33 as a clutch, so as to rotate the spindle.

The conical disk 36 is secured to the bracket 9a around the sleeve shank 5', by which the vessel 5 is secured on the upper end of the spindle; and the bottom 5a of the vessel is conically shaped to seat and bear upon the conical disk 36 as a brake to stop the rotation of the vessel.

10 The parts are so proportioned and arranged that the bottom of the vessel will normally bear upon the conical disk when the drive wheel and the friction disk thereon are in normal position freely below and disengaged from the friction disk 33 on the spindle; and that when the drive wheel is raised, its friction disk or the washer disk when used, will bear upward against and engage the friction disk on the spindle, and 15 will raise the spindle to elevate the conical bottom of the vessel clear above the conical disk 36, so that the vessel may be freely rotated by the drive wheel.

It is evident that as the drive wheel is raised, the flatwise abutment of the disk 32 with the disk 33 will permit some slippage until the conical bottom of the vessel is raised free of the conical brake disk 36, thus insuring a gradual assumption of the load by the 20 driving mechanism. Consequently, smoother operation without sudden shocks or strains in the machine and longer life of the wearing parts is effected.

As indicated above, when the steel washer disk 35 is interposed between the friction disks 32 and 33, the slippage is increased to further ease the starting of the spindle.

When the sleeve 19 in the lid-hinge actuating mechanism is in normal outward inoperative position, where it is held by the spring 20, as shown in Fig. 2, the lid 15 may be freely opened and closed, and the roller wheel 24 will ride freely on the cylindric inner end portion of the sleeve 19; and when it is desired to operate the apparatus, the lid being held open by one hand of the operator, the sleeve 19 is pushed inward into inoperative position by the other hand applied to the disk handle or button 19a, which is pushed and held inward to bring the cam 19d in the path of the roller wheel 24 while the lid is being closed, so that the roller will ride on the cam 19d which pushes the plunger rod downward and actuates the lever 25 for elevating the 25 friction disk drive wheel into flatwise operating bearing contact with the friction on the spindle disk, and raising the bottom of the vessel above the brake disk, for rotating the vessel and the receptacle therein.

When the roller wheel rides upon the cam 19d, the flange 19e on the inner end thereof engages the inner side of the wheel and prevents the sleeve from moving outward, until the lid is again opened and the roller wheel rides upward on the cam until it is

free of the flange, whereupon the spring 20 automatically pushes the sleeve outward so that the roller will ride upon the cylindric portion thereof; and in so doing, the plunger rod is pushed upward by the weight 70 of the drive wheel and the superposed spindle and vessels, bearing on the inner end of the lever 25, and all the parts drop downward into inoperative position with the bottom of the vessel bearing on the brake disk, 75 which stops the rotation of the vessel and the receptacle and permits the withdrawal of the clothes therefrom.

By the described construction and arrangement of the parts, it is impossible to operate 80 the spinning or rotating parts without first opening the lid and manually holding the cam in actuating position while closing the lid; thus making it safe for an inexperienced person to operate the machine without accidentally or unintentionally starting the spinning mechanism.

Moreover, the automatic formation and maintenance of the continuous liquid balancing wheel in the spherical-zone channel in 90 the vessel at a substantial interval from and around the outside of the clothes receptacle, renders it possible to spin the parts at a much greater speed than would otherwise be possible on a spindle operating in $\frac{1}{2}$ bearings. 95 And finally, the use of friction driving and brake means causes a gradual starting and stopping of the spinning parts, without any sudden straining of the bearing parts, and permits the apparatus to be safely operated 100 by an inexperienced person.

I claim:

1. A centrifugal apparatus including a vessel rotatable on a vertical axis, a receiving receptacle supported within in the vessel 105 for rotating therewith, the vessel provided with liquid outlet apertures spaced outward from the receiving receptacle a greater distance from the axis of the receptacle and the vessel than the radius of the receptacle, and forming a continuous spherical-zone channel of substantial width and depth for receiving liquid to form a balance wheel of substantial 110 volume and uniform segmental cross section throughout its peripheral length spaced freely from the outside of the receptacle. 115

2. A centrifugal apparatus including a vessel rotatable on a vertical axis, a receiving receptacle supported in the vessel for rotating therewith, and having an inverted 120 conical-zone wall in its lower part with an annular series of liquid outlet apertures at the upper end thereof, the vessel forming a continuous spherical-zone channel of substantial width and depth for receiving liquid 125 to form a balance wheel of substantial volume and uniform segmental cross section throughout its peripheral length spaced freely from the outside of the receptacle.

3. A centrifugal apparatus including a ves- 130

sel rotatable on a vertical axis, a receiving receptacle supported within in the vessel for rotating therewith, the vessel forming a continuous spherical-zone channel of substantial 5 width and depth for receiving liquid to form a balance wheel of substantially uniform segmental cross section throughout its peripheral length spaced freely from the outside of the receptacle, and having an annular series of 10 liquid outlet apertures at the lower side thereof spaced outward from the receiving receptacle a greater distance from the axis of the receptacle and the vessel than the radius of the receptacle, said apertures being 15 adapted to remain open at all times.

4. A centrifugal apparatus including an upright spindle mounted for rotating with a limited endwise movement, a stationary friction brake disk around the upper end of 20 the spindle, a member on the upper end of the spindle normally bearing on the brake disk, a friction disk on the lower end of the spindle, and a friction disk drive wheel normally located freely below the friction disk and 25 mounted for raising to bear flatwise upward against the friction disk for rotating the spindle and elevating the receptacle freely above the brake disk.

5. A centrifugal apparatus including an upright spindle with a vessel on its upper end, power means for rotating the spindle, 30 clutch means for engaging and disengaging the power means with the spindle, a case with a lid thereon for the vessel, a hinge between the lid and the case, normally inoperative mechanism between the hinge and the clutch for actuating the clutch, and manually actuated means on the hinge for selectively rendering the mechanism operative for 35 actuating the clutch for engaging the power means with the spindle by a closing of the lid and automatically disengaging them by an opening of the lid, including means whereby said manually actuated means is rendered inoperative as a result of the said opening of 45 the lid.

6. A centrifugal apparatus including an upright spindle with a vessel on its upper end, a stationary case having a hinged lid for 50 the vessel, and means for rotating the spindle actuated by a closing of the lid and automatically stopping the rotation by an opening of the lid, including a lid-hinge pintle, a journal bearing for the pintle having an annular socket in one end, a sleeve feathered on the pintle for telescoping in the socket, a spring in the socket urging the sleeve outward, an adjacent plunger-rod roller, and a cam on the sleeve normally outside the path 55 of the roller adapted to be moved into the path of the roller by pressing the sleeve inward against the action of the spring.

7. A centrifugal apparatus including an upright spindle with a vessel on its upper 65 end, a stationary case having a hinged lid

for the vessel, and means for rotating the spindle actuated by a closing of the lid and automatically stopping the rotation by an opening of the lid, including a lid-hinge pintle, a journal bearing for the pintle having an annular socket in one end, a sleeve feathered on the pintle for telescoping in the socket, a spring in the socket urging the sleeve outward, an adjacent plunger-rod roller, and a cam on the sleeve normally outside the path of the roller adapted to be moved into the path of the roller by pressing the sleeve inward against the action of the spring, there being a flange in the inner side of the cam engaging the inner side of 80 the roller when riding on the cam.

8. A centrifugal apparatus including an upright spindle mounted for rotating with a limited endwise movement, a stationary friction brake disk around the upper end of the 85 spindle, a member on the upper end of the spindle normally bearing on the brake disk, a friction disk on the lower end of the spindle, and a friction disk drive wheel having a washer disk thereon and normally located 90 freely below the friction disk and mounted for raising to cause the washer disk to bear flatwise upward against the friction disk for rotating the spindle and elevating the receptacle freely above the brake disk.

In testimony that I claim the above, I have hereunto subscribed my name.
